SNAP SEAL FASTENER

George C. Hurt, Warrenton, Oreg.

Application October 20, 1947, Serial No. 730,816

2 Claims. (Cl. 229—78)

1

This invention relates to novel and useful improvements in envelopes particularly those conventionally used in the mails.

The general object of this invention is to seal a body portion and flap of an envelope by mechanical means obviating the use of glue and the like.

Another purpose of this invention is to provide receptacle means on the flap engageable with complementary locking means partially projecting within the envelope.

Another purpose of this invention is to provide the receptacle means of such configuration as to import guide means for urging selected legs of the locking means in the closed, latched position.

Another purpose of this invention is to provide a device of the nature to be described which is extremely simple to actuate, thereby rendering utility of the present invention economical from a time standpoint.

Ancillary objects and features of novelty including commercial feasibility, will become apparent to those skilled in the art in following the description of the preferred embodiment of the present invention, illustrated in the accompanying drawing, wherein:

Figure 1 is a perspective view of the preferred form of the present invention;

Figure 2 is an enlarged sectional view of the clamp in one phase of operation;

Figure 3 is an elevational end view of the bendable locking means positioned on the flap of the envelope;

Figure 4 is a perspective view of the receptacle positioned mostly within the envelope and provided for the purpose of receiving the bendable locking means therein, and;

Figure 5 is a perspective view of the locking means shown in a flat or open position, prior to installation on the flap of the envelope.

Referring now in detail to the illustrated preferred embodiment of the present invention, like reference characters are used throughout to indicate similar elements thereof.

This invention has been developed to provide an embodiment which is capable of rendering the task of sealing envelopes far more desirable, expedient and easy. As is well known to those having the task of sealing numerous envelopes throughout many hours of the day, the operation of either licking or sponging the mucilage on the envelope becomes rather difficult. In this invention, the only requisite for sealing an envelope efficiently is simply squeeze the flap in the proper

2

position and the job is completed. In carrying out this function, the following structure is provided.

An envelope is provided with a body portion 10 and a conventional flap 12. Complementary portions of the locking means are provided on the body portion 10 and flap, respectively.

Going to Figure 4, the receptacle which is received on the body portion is shown in detail. 10 Here, a receptacle 14 having a concave inner surface is provided with a marginal flange 16 there-around. Extending from this marginal flange is a plurality of lugs 18.

Going now to Figure 2, it will be noted that 15 the said lugs 18 are bendable about their inception points for the purpose of retaining in frictional engagement therewith, the body portion 10. Of course, a suitable hole may be punched in the said body portion prior to the insertion 20 of the receptacle 14 in order to facilitate manufacture of the invention. It is also noted that the majority of the said receptacle 14 is received entirely within the said envelope.

Going now to Figures 3 and 5, there is dis- 25 closed a locking means which has the preferable configuration as follows: A rounded central section 20 is provided with a plurality of prongs 22 extending therefrom in a radial manner. Also extending from the said rounded central portion 20 is a pair of oppositely aligned prongs 24 and 26, respectively. These prongs 24 and 26 are bent first 180° thence 90° in the opposite direction. The next bend is preferably about 110° in the same direction as the 90° bend. This last mentioned bend provides extensions 28 and 30 on the said prongs 24 and 26, respectively. These last mentioned prongs 24 and 26 are adapted to extend in the receptacle 14 and be bent therein. The inner concave surface of the receptacle 14 assists in bending as well as guiding the said prongs in the said receptacle. The members 22 are bent at substantially 90° as shown in Figure 3 for the purpose of inserting the same in the flap 12 of the envelope. After insertion, these members 22 may be bent back again in the original position or if desired, bent at an angle of substantially 180° to the original position disclosed in Figure 5.

In operation of the invention it will be noted that the preferential material of construction is bendable and pliable. Accordingly, after insertion of the said legs or prongs 24 and 26, respectively, into the receptacle 14, the entire assem- 50 blage of locking means may be squeezed together to any desired thickness. This, of course, renders

utility of the invention extremely rapid since all that is necessary to effect a seal between the flap and body portion is simply place the complementary locking means together and flatten the same by a simple press of the finger. Further, assurance against unauthorized inspection of the contents of the envelope is provided since substantially the only method of entry to the envelope is by tearing the flap or other associated marginal edge of the envelope.

It will be noted that there is illustrated an embodiment of the invention disclosing only one set of complementary locking means. However, if desired, any number may be utilized on a single envelope in accordance with the dictates of sound engineering or design principles. Further, the locking means are so placed as not to interfere with the efficient operation of mechanical envelope opening devices.

Due to the extreme simplicity achieved by the present invention, a further description thereof is deemed unnecessary. However, it is apparent that various departures might be made herein without departing from the spirit of the invention. Accordingly, limitation is sought only in accordance with the scope of the following claims.

Having described the invention, what is claimed as new is:

1. An envelope including a body portion having a flap secured thereto, a receptacle secured to said portion and bendable locking means secured to said flap lockingly engageable with said receptacle, said receptacle having a concave wall and a marginal flange extending therearound

said marginal flange having an opening to receive said locking means, bendable lugs extending from said flange and cooperating therewith to frictionally engage said body portion, said bendable lugs being substantially U-shaped, one of the legs of each of said U-shaped lugs being a portion of said flange and the other leg being substantially parallel thereto, terminating inwardly of the outer edge of said receptacle.

2. An envelope including a body portion having a flap secured thereto, a receptacle secured to said portion and bendable locking means secured to said flap engageable with an opening in said receptacle, said locking means including a base, means for securing said base to said flap, prongs having angular extensions projecting and bendable within said receptacle, said receptacle having a concave wall for guiding said prongs, a marginal flange around said wall with said opening therein, bendable lugs remote from said concave wall extending from said flange at the edge of said opening for lockingly engaging said body portion.
